UNITED STATES PATENT OFFICE.

JAMES M. SULLIVAN, OF CHICAGO, ILLINOIS.

COMBINATION-TOOL.

SPECIFICATION forming part of Letters Patent No. 651,398, dated June 12, 1900.

Application filed July 10, 1899. Serial No. 723,370. (No model.)

To all whom it may concern:

Be it known that I, JAMES M. SULLIVAN, a citizen of the United States, residing at Chicago, county of Cook, State of Illinois, have 5 invented a certain new and useful Improvement in Combination-Tools; and I declare the following to be a full, clear, and exact description of the invention, such as will enable others skilled in the art to which it pertains to 10 make and use the same, reference being had to the accompanying drawings, which form a part of this specification.

My invention has for its object the production of a combination-tool which shall 15 embrace in the one tool a hatchet, a hammer, a nail-puller, a screw-driver, a wire-cutter, a scraper, and a pair of tongs.

The details of the invention will be herein-after more fully described and claimed.

20 In the drawings, Figure 1 is a perspective view of my tool. Fig. 2 is a side elevation of a portion. Fig. 3 is a horizontal section on the line 3 3 of Fig. 2. Fig. 4 is a vertical section on the line 4 4 of Fig. 2. Fig. 5 is a perspective view of the head portion. Fig. 6 is another perspective view thereof. Fig. 7 is a detail of one of the cutting-jaws.

In carrying out the invention, A represents a suitable head, and preferably formed in 30 integral therewith is a hatchet-blade B. Extending vertically in the head and at the edge thereof is a slot C, more or less dovetail in shape, although the walls of the slot are preferably rounded, as shown.

35 D is a metallic part of the handle, the end provided with a rounded projection d to correspond with the slot C. The handle is engaged to the head by sliding the projection or flange d into the slot C and turning or 40 clenching the edges of the head, as at d², to hold the handle in place.

The handle D is preferably formed of sheet metal bent as shown, with one edge d' turned into a flange to strengthen the handle. This 45 edge d' is extended out from the handle D

and curled to strengthen it, as at d². Surrounding the portion d² is a wooden part E of the handle, the end fitting in the hollow portion of the handle D, while the portion d² projects beyond the wooden handle, where a 50 screw-driver F is engaged. A cap F', engaged to the portion d², holds the wooden handle in place.

G is a hammer-head formed of sheet metal and bent to form a flat hammer portion g, 55 with projecting flanges g', having rounded ends or edges g². The head A is provided with a slot A' to receive these edges g², the metal of the head being turned over or clenched, as at g³, to hold the hammer-head 60 in place. Projecting on the head A and preferably a part thereof, although it may be secured thereto, if desired, is a stationary jaw H, having a rounded cutting edge h. Pivoted to the head A is a lever J, one end forming the handle J', while on the other end is another jaw J², having a cutting edge j. The face of each jaw is serrated, as shown at j'. The cutting edges form wire-cutters, while the two jaws form pipe tongs or pliers or a 70 wrench or the like. Projecting from the hammer-head G is a sharpened edge K, which forms a scraper. In the head may also be provided a slot M to form a nail-puller.

What I claim is—

75 A combination-tool comprising a hatchet-head provided with a handle, said head provided with a stationary jaw and a lever pivoted to said head and provided also with a jaw, said lever extended to form a handle 80 and made concave so that it fits over and closely embraces the handle of the hatchet, substantially as described.

In testimony whereof I sign this specification in the presence of two witnesses.

JAMES M. SULLIVAN.
